(57) CLAIM

The ornamental design for a puzzle game, as shown and described.

DESCRIPTION

FIG. 1 is a front view of a puzzle game, showing my design;

FIG. 2 is a left side view thereof;

FIG. 3 is a right side view thereof;

FIG. 4 is a rear view thereof;

FIG. 5 is a bottom view thereof; and,

FIG. 6 is a top view thereof.

The broken lines in the figures and the lower-opacity areas within the broken lines show portions of the puzzle game that form no part of the claimed design.

1 Claim, 6 Drawing Sheets
